UNITED STATES PATENT OFFICE.

ORMOND E. HUNT, OF DETROIT, MICHIGAN, ASSIGNOR TO PACKARD MOTOR CAR COMPANY, OF DETROIT, MICHIGAN, A CORPORATION OF MICHIGAN.

HEADLIGHT.

1,321,827.

Specification of Letters Patent.

Patented Nov. 18, 1919.

Application filed May 3, 1916. Serial No. 95,133.

To all whom it may concern:

Be it known that I, ORMOND E. HUNT, a citizen of the United States, and resident of Detroit, Wayne county, State of Michigan, 5 have invented certain new and useful Improvements in Headlights, of which the following is a specification.

This invention relates to an improvement in motor vehicles and particularly in 10 the headlights therefor.

One object of this invention is to provide a single unitary headlight having two separate recesses, one above the other, both closed by a one piece bezel.

15 Another object of the invention is to provide a single unitary headlight having two lamps differing in intensity, the weaker being for city use and the stronger being for country use, a separate reflector for each 20 lamp and a one piece bezel covering both lamps.

Other objects of the invention will become apparent from the following description, taken in connection with the drawings 25 which form a part thereof, and in which:

Figure 1 is a front elevation of a headlight made in accordance with this invention;

Fig. 2 is a longitudinal section of such headlight taken along the line 2—2 of Fig. 1; 30 Fig. 3 is a detail view of the hinge construction; and

Fig. 4 is a section on the line 4—4 of Fig. 1 showing the means for holding the bezel in position.

35 One of the requirements of a headlight to be used on motor vehicles is that the intensity of the light should be alterable. Many means of attaining this result have been tried such as changing the focus of the 40 lamp or placing a screen in front of the lamp, when a light of low intensity was desired. Headlights have also been built having two lamps of different intensity with a single reflector, and double headlights 45 each made up of two entirely separate lamps have been tried. This invention consists in a single unitary headlight with two separate lamps having a one piece bezel provided with two openings corresponding with the 50 lamps.

The reference numeral 10 is applied to the body portion of the headlight which contains two recesses of unequal size, the larger 11, being above the smaller 12. These recesses, each cup shaped and circular at the

outer edge where they contact with the cover, are each provided with a reflector 13 and lamp 14. The reflector is separated from the outer wall of the body portion and in the space so provided are positioned the 60 electrical connectors 15 between the lamps 14 and the binding posts 16 to which are to be secured the outside connections (not shown) from any power supplying means. The reflector 13 and lamp 14 in the larger 65 recess 11 are of greater concentration and higher intensity respectively than the reflector and lamp in the smaller recess 12, and they consequently illuminate the road farther ahead. The lamps may be and generally are used independently depending upon the amount and concentration of light desired.

The body portion 10 may be integral but is here shown as made up of two members 75 one containing the larger recess 11 and the other the smaller recess 12. These members are welded or otherwise connected together at 17, the line of joining being concealed by the plate 18. The outer edge of the body 80 portion is offset as at 19 to provide a shoulder on which rests an intermediate member 20 secured to the body portion. The reflectors 13 are fastened to the member 20 by nut and bolt connections, such as is 85 shown for example at 21, a strip of felt 22 being introduced between the reflectors and the member.

The recesses are closed by a cover 23 composed of a one piece bezel 24 having two 90 openings filled by panes of glass 25 and 26 mounted therein, through which the rays pass from the lamps. The outer edge of the bezel is turned back on itself as at 27 nearly to the edges of the panes of glass, 95 and carries plates 28 which extend over the panes and hold the same against the bezel, felt 29 being inserted on either side of the glass in order to prevent any leakage of moisture. This part 27 also fits tightly 100 around the felt 22 to make a tight joint between the cover and the body portion.

The cover is mounted on the body portion by a hinge 30, one member 31 of which is inserted between the bezel and the turned 105 back portion and secured to the latter, and the other member 32 of which is inserted through a slot in the body portion 10 and is held in position against the inner surface of that portion by screws 33. The effect of 110

such a construction is to conceal the greater part of the hinge mechanism. The cover is fixedly held in place by fastening means 34, between the larger pane 25 and smaller pane 26. One of said means is illustrated in detail in Fig. 4 and consists of an internally threaded screw 35, the head of which coincides with the outer surface of the bezel 24, engaging a threaded stud 36 fixedly secured 10 in the intermediate member 20 and extended outward through a felt strip 22.

A single embodiment only is shown and described but it is obvious that other modifications may be made which fall within the 15 limits of this invention.

Having thus described my invention, what I claim and desire to secure by Letters Patent is:—

1. In a headlight, the combination with 20 two lamps of different sizes and two reflectors therefor, of a body portion having two lamp recesses separately conforming in size and shape to said lamps and their respective

reflectors, a common front cover for said recesses, a hinge connection between the 25 cover and one point on the body portion, and fastening means for said cover at a point on the body portion between said recesses, said means drawing the cover as a whole tightly against the front of the body portion. 30

2. In a headlight, the combination, with 35 a pair of lamps and reflectors behind the lamps, of a body portion having two recesses, one larger than the other and respectively conforming in size and shape to said reflectors, a front cover common to said recesses and having separate panes corresponding to the latter and having a hinged connection to said body at a point on the body portion remote from the smaller recess, 40 and fastening means for said cover at a point on the body portion between the two recesses.

In testimony whereof I affix my signature.

ORMOND E. HUNT.
